UNITED STATES PATENT OFFICE.

PETER E. PASKAL, OF TORONTO, ONTARIO, CANADA.

CHILD'S CRADLE.

1,282,927.

Specification of Letters Patent. Patented Oct. 29, 1918.

Application filed June 8, 1918. Serial No. 238,963.

To all whom it may concern:

Be it known that I, PETER E. PASKAL, a subject of the Emperor of Austria, residing at Toronto, Province of Ontario, and Dominion of Canada, have invented certain new and useful Improvements in Children's Cradles, of which the following is a specification.

This invention relates to improvements 10 in cradles, such as are used by children, and has as its special object to provide a cradle, which may be rocked or oscillated in one direction by a foot lever, return oscillation being accomplished by a spring, therefore 15 providing an easy and convenient method of actuating the cradle.

A further object is to provide means which prevent over action of the cradle, either due to the rocking effect imparted or 20 to the movement of the child therein.

These and other like objects are attained by the novel construction and combination of parts hereinafter described and shown in the accompanying drawings, forming a 25 material part of this disclosure, and in which:—

Figure 1 is a side elevational view, showing a cradle made in accordance with the invention.

30 Fig. 2 is a top plan view of the same.

Fig. 3 is an elevational view, looking from the foot end of the cradle, and

Fig. 4 is a fragmentary, vertical sectional view, taken on line 4—4 of Fig. 2.

35 Mounted upon a fixed platform 10, which extends entirely below the cradle, are a pair of blocks respectively 11 and 12, having within them recesses 13 and 14, receivable of the bars 15 and 16, formed on the base 40 18 of the cradle, and through which pass the pivot pins 35, on which the cradle rocks. The base 18 of the cradle has attached to it a head board 20, and a foot board 21.

Extending between these vertical elements 45 are rails 22, connected with the base 18 of the cradle, by a plurality of vertical bars 23, the same being so designed as to prevent an infant from falling out from either side of the cradle.

At the end of the outer bar 15, is a pin 50 26 engaged by a bar 28, the same acting as a lever, being fulcrumed near its center, upon a bracket 29 secured to the platform 10, the outer, free end 30 of the lever bar, being extended to a point where it may be 55 conveniently operated.

Fixed transversely upon the platform 10, near the foot board 21, is a bent flat spring 32, adapted to press against the cradle platform 18, upward on the side opposite to the lever bar 28. Thus as the lever end 30 is depressed, it causes the cradle to rock or oscillate upon pins 35, engaged between the blocks 11 and 12, and lugs 15 and 16, while the spring 32, upon 60 release of the lever 30, causes the cradle to rock in the opposite direction.

In order to prevent over-operation of the cradle, whereby the infant might be spilled out, there is arranged upon the platform 10, at the extreme foot end, a triangular frame or standard 37, carrying at its apex, a fixed pin 38, having a head 39 on its inner end, which passes through an arcuate slot 40, formed in the upper end of the foot-board 21, thus preventing the frame from 65 70 75 rocking or oscillating to a dangerous degree.

The foregoing description taken in connection with the drawing, is believed to 80 make the construction and manner of the operation clear, and having thus described my invention what I claim as new, and desire to secure by Letters Patent, is—

1. In a cradle, the combination with a 85 fixed platform, raised elements extending therefrom, a cradle having its base pivoted in said raised elements, a lever fulcrumed on said platform, said lever engaging with the head of said cradle, whereby it may be 90 oscillated in one direction, a bent flat spring secured to said platform, contacting with said cradle, said spring exerting a pressure opposed to that of said lever, and means of preventing over oscillation of said cradle. 95

2. In a cradle, the combination with a fixed platform, a cradle body journaled to rock on said platform, a lever extending

longitudinally of said platform, adapted to rock said cradle in one direction, resili-
ent means adapted to operate said cradle in the opposite direction, a standard on
5 said platform, said standard having a pin rigidly engaged at its upper end, and an

arcuate slot formed in the foot-board of said cradle in which said pin engages, whereby its movement is limited.

In testimony whereof I have affixed my 10
signature.

PETER E. PASKAL.
